(57) **CLAIM**

The ornamental design for a luminaire, as shown and described.

DESCRIPTION

FIG. 1 is a perspective side view of the design for the luminaire of the present invention;

FIG. 2 is a side elevational view thereof;

FIG. 3 is a top plan view thereof;

FIG. 4 is a bottom plan view thereof; and,

FIG. 5 is an end view thereof, the opposite end view being identical.

The broken lines shown on the drawings are for illustrative purposes only and form no part of the claimed design.
